INFANT'S GYM TOY

Paul D. Snyder, East Aurora, N.Y., assignor to The
Quaker Oats Company, Chicago, Ill.

Filed Jan. 7, 1974, Ser. No. 431,166

Term of patent 14 years

Int. Cl. D21—01

U.S. Cl. D34—15 J

FIG. 1

FIG. 2

FIG. 3

FIG. 4

FIG. 5

FIG. 1 is a front perspective view of an infant's gym toy showing my new design;

FIG. 2 is an end elevation thereof as viewed from the left in FIG. 1, showing the parts in different orientation for the purposes of illustration;

FIG. 3 is an end elevation thereof as viewed from the right in FIG. 1, showing the parts in different orientation for the purposes of illustration;

FIG. 4 is a view taken along the line 4-4 in FIG. 2; and

FIG. 5 is a view taken along the line 5-5 in FIG. 3.

I claim:

The ornamental design for an infant's gym toy, substantially as shown and described.
